SOUND RECORDING APPARATUS

Jackson O. Kleber, Long Island City, N. Y.

Application November 28, 1933, Serial No. 700,111

24 Claims. (Cl. 179—100.3)

This invention relates to the photographic recording of sound and associated records on films. More particularly the invention relates to apparatus for making a variable width sound record on a movable film, wherein the image of an illuminated slit or line source of light is produced on the film transversely of the direction of movement of the film, and in which the image of the slit or source of light is varied in length by a mechanically oscillatable controller to define the profile of the sound track on the film.

This application is a continuation in part of my application Serial Number 391,201 filed September 9, 1929, and issued as Patent No. 1,937,089, Nov. 28, 1933, for a Machine for recording and reproducing sound motion pictures.

An object of the present invention is to provide improved and simplified apparatus for producing sound records of the kind referred to.

Another object is more effectively to control the opening through the illuminated slit or to control the area of the image on the film in response to a given displacement of the mechanical controller which defines the profile of the sound track on the film.

Another object is to increase the frequency range of sounds effectively recorded on the film.

Another object is to improve the operation of the oscillatable controllers for varying the profile of the sound track by rendering the controllers properly aperiodic in their movements.

Other objects are to increase the amplitude of variations in width of the sound track for a given intensity of sound, to improve the quality of the record, and to produce a sound record of such form as to reduce disturbing noises which tend to be reproduced when the film is passed through a sound reproducer.

In accordance with one modification of the present invention, apparatus is provided for making a variable width sound record on a movable photographically sensitive film. A source of light transmits a beam to the film through a slit in a screen, producing an image of the slit on the film transversely of the direction of movement of the film. A plurality of controllers, such as sound controlled oscillatable shutters or mirrors, are provided to act on different parts of the image of the slit on the film, one controller varying the position of one terminus of the line image of the slit and another controller varying the position of another terminus of the line image.

One form of oscillatable shutter has an edge thereof inclined across and arranged to variably intercept the path of light through one end of

the slit. Another shutter operating in conjunction with the first shutter is inclined across and arranged to variably intercept the path of light through the other end of the slit independently of the first shutter. By arranging the shutters so that one is selectively operable at a higher natural frequency of oscillation than the other shutter, a more faithful record of the sound may be obtained and sound waves having a wider range of frequencies may be recorded on the film. Another application of the two-shutter or two-controller apparatus reduces disturbing noises by reducing the area of the opaque part of the negative film, thus reducing the area of the transparent part of the final positive film during intervals when the sound amplitude or the amplitude of the controller is small or negligible. In this case one shutter or controller produces the sound record, while the other shutter is controlled by a detector operated under sound control in an arrangement for producing a quick response of the shutter for increases of amplitude and for producing a retarded operation of the shutter in response to a decrease of sound amplitude. In other forms of apparatus illustrative of the present invention, mirrors are employed to accomplish these results.

In a modified form of the invention, two separate shutters define the same end of the line of light to be produced on the film. Each shutter has an edge inclined across the line source of light, the two edges being inclined oppositely with respect to the line. The shutters are arranged to oscillate in unison and to maintain the point of intersection of their inclined edges directly over the longitudinal center line of the slit or line of light. This arrangement avoids a certain amount of distortion of the sound incident to the use of a single inclined shutter.

These and other objects of the invention will be more clearly understood by reference to the following detailed description in connection with the drawings, in which:

Fig. 1 is a diagrammatic view of sound recording apparatus illustrative of one form of the invention, in which an independent shutter is provided at each end of a light slit.

Fig. 2 shows a fragment of film produced by the apparatus of Fig. 1.

Fig. 3 shows a modification of a part of the apparatus of Fig. 1.

Figs. 4 and 5 show fragments of films produced by the apparatus of Figs. 1 and 3.

Fig. 6 shows a modification of the shutter controlling apparatus of Figs. 1 and 3.

Fig. 7 is a modification of Fig. 1 adapted to reduce undesired noise which may be reproduced by transparent portions of the film.

Fig. 8 shows a fragment of the negative film produced by the apparatus of Fig. 7.

Fig. 9 shows a fragment of the positive film copied from the negative shown in Fig. 8.

Fig. 10 is a diagram showing different places in the optical system where the apparatus described herein may be introduced.

Fig. 11 shows a modified form of light deflecting apparatus.

Fig. 12 shows a modification of the apparatus of Fig. 11.

Fig. 13 is a diagram of an oscillation damping device.

Figs. 14 and 15 show modified forms of shutters.

In Fig. 1 the lamp 1, or other suitable concentrated source of light, projects a beam of light to the photographically sensitive film 2, which is guided and positioned by rollers 3 over which the film feeds. An optical system, comprising the condenser lenses 4 and the objective lenses 5 may be either of spherical or cylindrical form. A screen 6 intercepting the light beam from source 1 to film 2 has a slit 7 therein positioned with respect to the optical system 4, 5, so that light from condenser 4 is concentrated on the slit, and an image of the slit or line source of light is projected on the film at 8 transversely of the direction of movement of the film. A shutter 9 having an edge 10 which is inclined across one end of slit 7 is pivoted at 11, so that it may oscillate under the control of armature 12 attached to the shutter transversely of the slit. Another shutter 13 has an edge 14 inclined across the other end of slit 7. Shutter 13 is oscillated around pivot 15 by means of armature 16. Shutters 9 and 13 variably intercept the path of light through the respective ends of slit 7 which they overlap and thus vary the position of the two edges of the light beam corresponding respectively with the two edges of the sound track. Sound waves impressed upon microphone 17 or other suitable pick-up devices produce sound controlled currents which are increased in amplitude by amplifier 18.

Output circuit 19 of the amplifier has low pass filter 20 and high-pass filter 21 connected therein. Electromagnet 22 controls armature 12 and is connected with filter 20. Currents of a frequency below a value pre-determined by the upper cut-off frequency of filter 20 selectively energize magnet 22, while electromagnet 23, controlling armature 16, is selectively energized only by currents above said pre-determined frequency, determined by the low cut-off frequency of filter 21.

In operating the apparatus of Fig. 1, speech or other sound waves actuating transmitter 17 produce electric currents, the low frequency components of which actuate shutter 9 and the high frequency components of which actuate shutter 13, so that the position of one terminus of the line representing the image of the slit on the film is varied at a low frequency by shutter 9 and the position of the other terminus of the line image is varied at a high frequency by shutter 13, while the film is fed transversely to the line image, thereby producing a record as shown in Fig. 2. The end of the line varied at a low frequency, traces the low frequency profile 24, while the end of the line varied at a high frequency traces the profile 25. The two profiles or edges of the sound track are thus varied in accordance re-

spectively with two currents of different character, one a low frequency current and the other a high frequency current.

Fig. 3 shows more fully than Fig. 1, the arrangement for supporting the shutters and maintaining them in a normal position about which the shutters oscillate. To accomplish this purpose each armature 12, 16, is supported at one end of a spring 26, the other end of each spring being fastened to a fixed support 27. Spring 26 yields in response to the oscillations of the shutter and restores the shutter to its normal position. Shutter 28 is of larger dimensions or has a larger mass than shutter 29, Fig. 3, or may be provided with a lighter spring 26 than the spring for shutter 29, so that shutter 29 has a higher natural frequency of oscillation than shutter 28, and is thus selectively operable at a higher frequency than shutter 28.

By suitably mechanically tuning shutters 28 and 29, the electrical selectivity obtained by filters 20 and 21 may not be necessary where extreme selectivity is not desired and the filters may be removed from the circuit by transferring switches 30 and 31 to their upper positions, thus eliminating the filters from the circuit. It will be understood that filters 20 and 21 may similarly be omitted in Fig. 1, in which case shutters 9 and 13 vibrate at the same frequency and produce a record as shown in Fig. 5, wherein the profile 33, at one side of the sound track is similar to the other profile 34 at the other side of the track.

If one of the shutters 13, in Fig. 1, or 29, in Fig. 3, be made non-responsive to current, as by opening the control circuit therefor, or leaving it de-energized, only one of the shutters operates to produce a variable profile 32, as shown in Fig. 4. It will be understood that magnets 22 and 23 may be connected to independent circuits instead of to a common circuit 19, and may thus be employed to produce two independent profiles on a single sound track of the type shown in Fig. 5. One of these profiles may represent a complete sound record, while the other profile of the same track may be utilized to control the operation of the apparatus for reproducing the sound recorded on the film, as, for example, the volume of the sound or some other characteristic or operation which it is desired to control in connection with the reproduction of the sound.

In Fig. 6, the armatures 36 and 37, controlling shutters 38 and 39, are both operated by electromagnet 40, which is controlled by the sound controlled currents representing the sound which is to be recorded. In this form of apparatus the single magnet 40 takes the place of magnets 22 and 23, Figs. 1 and 3. When shutter 38 is to have a different frequency response from shutter 39, as in the case of the shutters of Figs. 1 and 3, mechanical tuning of shutters 38 and 39 may be provided.

In order to reduce disturbing noises which tend to be reproduced when the film is passed through the sound reproducer, it has been found desirable to reduce the area of the transparent portions of the film which are to be exposed to light in the reproducing machine, as shown in Fig. 9 by the positive film having the opaque area defined by profile 49, closely following the amplitude or intensity variations of the sound current represented by profile 48.

Fig. 7 provides apparatus for producing a sound record in which disturbing noises of the kind referred to are reduced. Sounds impressed upon the microphone or pick-up device 48 produce cur-

rents amplified in amplifier 41, the amplified currents being transmitted through filter 42 to shutter magnet 22. Filter 42 is designed to limit the frequency of response of magnet 22 to a range which it is desired to record on the film, but may be omitted from the circuit, if desired. A part of the amplified current from amplifier 41 is transmitted to detector 43, connected with the same circuit supplying current to magnet 22, and having its output circuit connected through filter 44 with shutter magnet 23. Detector 43 may be any suitable form of detector or rectifier. Low pass filter 44, in conjunction with detector 43 and magnet 23, limits the frequency response of the magnet to frequencies below the audible range, so that magnet 23 can not produce an audible sound record, but produces a low frequency profile which follows closely the amplitude or intensity variations of the sound current. The combination of detector 43, filter 44 and magnet 23, is such that it is possible to retard the de-energization of magnet 23 as compared with the time required for energization thereof by the detected current. One method of accomplishing this result is to adjust low pass filter 44 to introduce the desired delay characteristic.

Fig. 8 shows a sound track produced as a photographic negative by the apparatus of Fig. 7. Profile 45 represents a record of the sound, while the lower frequency profile 46, produced by rectified sound current passing through magnet 23, follows closely the points of maximum amplitude of profile 45, but since the response of magnet 23 is limited to frequencies below the audible range, profile 46 does not show the audible frequency variations seen in profile 45. It will also be noted that profile 46 at point 47 is spaced somewhat further from profile 45 than at the point marked 46, thereby showing a more rapid energization of magnet 23 and a retarded de-energization of the magnet as the image of the light source projected on the film moves along the film in a downward direction in Fig. 8.

Fig. 9 shows a positive print made from Fig. 8. The transparent area between profiles 48 and 49 will be seen to have a much smaller extent than if the opaque area defined by profile 49 had been omitted. This form of record, having a reduced area of transparency, has a correspondingly small tendency to produce undesirable noises from irregularities in the transparent area of the film.

Fig. 10 shows the source of light 1, transmitting light through condenser 4, slit 50, objective 5, focus 51, objective 52 to focus 53 on film 2. The shutter arrangement shown in Figs. 1, 3 or 6 may be substituted in Fig. 10 directly at slit 50, or with slit 50 in the position shown, the shutters may both be located at point 51 or at point 53, in the path of light forming the image 53 on film 2; or if desired one shutter of an associated pair, such as 8, 13, Fig. 1, may be located at one of the points 50, 51, or 53, and the other shutter of the pair located at any other of these points. It will also be understood that the lamp source 1 may be placed sufficiently close to slit 50 to take the place of the combination of source 1 with condenser 4. Also, slit 50 may be moved to point 51 or 53.

It will be noted that when the source 1 is placed sufficiently close to slit 50 to avoid the use of condenser lenses 4, and when the slit 50 together with the shutters are placed at point 53, as referred to above, lenses 5 and 52 are obviously unnecessary, and the resulting combination is of extremely simple construction. In most cases,

however, the arrangement of the slit and shutters at the position 50 between lenses 4 and 5, as in Fig. 1, is to be preferred.

In Fig. 11 two plane mirrors 60 and 61 are coupled together near adjacent portions or edges by a common flexible yoke 62. The mirrors extend in opposite directions from the place of coupling and have hinged supports 63, 64, at points on the mirrors remote from coupling yoke 62. Rod 65 transmits vibrations from armature 66 to yoke 62 and mirrors 60, 61, thereby causing the mirrors to oscillate on hinges 63, 64. Armature 66 in turn is similar to armatures 12 and 16, Fig. 3, and is vibrated by electromagnet 67, energized by sound controlled currents. Mirrors 60 and 61 are so adjusted that they are substantially parallel in their normal, undeflected position. The source of light 1, transmits light through the condenser lenses 4, then through slit 7 in opaque screen 6, then through objective lenses 5 to mirrors 60, 61, from which the light is reflected to film 2, to produce an image thereon of the line of light defined by slit 7. Displacement of armature 66 causes the mirrors to depart from parallelism, thereby producing a double profile on the sound track on film 2, as shown in Fig. 5.

If desired, the mirrors may be operated by independent magnets 22, 23, as shown in Fig. 12. These magnets may be responsive, respectively, to different frequencies, as described in connection with Fig. 1. Magnet 22 may have a natural resonance characteristic of low frequency and magnet 23, a natural resonance characteristic of higher frequency. Magnet 22 vibrates armature 12, thereby oscillating mirror 60 at low frequency, while magnet 23 vibrates armature 16, thereby oscillating mirror 61 at a high frequency. The operation of armatures 12 and 16 is at the frequencies described in connection with Fig. 1, and it will be understood that the use of filters for selecting these frequencies, as shown in Fig. 1, or the use of other suitable frequency selecting means for this purpose, comes within the scope of the present invention. The record produced by mirrors 60, 61, in Fig. 12 is of the type shown in Fig. 2, as described in connection with Fig. 1. If desired, magnets 22 and 23 may be responsive to the same range of frequencies to produce independent records on the same sound track as shown in Fig. 5.

In some cases it is desirable that the mirrors or other controllers be properly damped so as to be rendered substantially aperiodic in their movement throughout the range of frequencies impressed thereon. For this purpose it is advisable to apply the damper directly to the vibrating element, for example, the mirror, on account of the likelihood of independent vibration of the individual parts of the moving system. In doing this, care must be taken not to introduce so much damping as to prevent sufficient free movement of the mirror or controller; however, the damping should be sufficient to prevent distortion due to pronounced resonance of the parts.

In overcoming these difficulties it has been found that a mirror of small size may have its oscillations damped by a damping device such as is shown in Fig. 13, wherein the mirror 54 having a hinge support 55 at one edge thereof, and armature 56 connected therewith, is provided with the damping element 57 under another edge of mirror 54 remote from the hinge 55. The damper 57 may be of any suitable material having a texture which is not too hard. Sponge rubber has been found to be very satis-

factory for this purpose. It will be understood that a piece of sponge rubber similar to the element 57, Fig. 13, may be employed to damp the oscillation of any of the controllers described herein. For example, a piece of sponge rubber may be inserted between the magnet and its associated armature in any of the controller units described herein.

The form of shutter 65' shown in Fig. 14 is similar to the shutters of Figs. 1 and 3, having the inclined edge 10 cooperating with slit 7 and oscillatable around pivot 11. Shutter 65', however, has an arm 66 terminating in a spring extension 67 secured to fulcrum 68. Arm 66 is vibrated by armature 12 operated by magnet 22.

Fig. 15 shows a still further form of shutter arrangement, having two separately oscillatable shutters 10 and 11, having pivots 12, 13, about which the respective shutters oscillate. Shutter 10 has an edge 14, and shutter 11 has an edge 15, inclined across the slit and arranged to define the same end of the line of light to be formed by light passing through the slit 7. Edges 14 and 15 are inclined oppositely with respect to the slit or line source of light 7 and intersect each other directly over the longitudinal center line of the slit or line of light, the shutters being arranged to oscillate in unison transversely of the line of light to vary the length of the line of light, while maintaining the point of intersection of edges 14, 15, over said center line. A single magnet 16 separately actuates armature 17 attached to shutter 10 and armature 18 attached to shutter 11. This double form of shutter has the advantage over the single shutter, shown in Figs. 1, 3, 6 and 7, of symmetrically intercepting the light through slit 7, thereby avoiding a certain amount of distortion introduced by the use of a single shutter. It will be understood that a double shutter of the form shown in Fig. 15, may be substituted for each of the single shutters shown in Figs. 1, 3, 6, and 7.

The shutters shown in Figs. 14 and 15 may be utilized in a system such as shown in Fig. 10. Shutter 65' of Fig. 14 may be inserted at any one of the points 50, 51 and 53, Fig. 10, to variably intercept the light through one end of the slit 50, and a similar shutter may be placed at any one of the points 50, 51 or 53 to variably intercept the light through the other end of slit 50. Slit 50 may alternatively be located at position 51 or 53. In a similar manner the shutter arrangement of Fig. 15 may be inserted at any one of the points 50, 51 or 53 of Fig. 10, to control the light through one end of slit 50, and a similar shutter arrangement inserted, if desired, to control the light through the other end of slit 50.

When one of the light modulators of Fig. 14 or Fig. 15, is located at each end of the slit in the position 50, Fig. 10, as referred to above, it will be seen that the relationship of the modulators to lenses 4 and 5 and the other elements, is similar to that shown in Fig. 1, and for most purposes such a location of the modulators is to be preferred.

In each of the cases where the line of light is independently intercepted at its two ends, as in Fig. 1, for example, a given displacement of each shutter produces a greater amplitude of variation of width of the sound track than is produced by a shutter operating with the same displacement in conjunction with only one end of the slit.

Various other modifications and changes will be obvious to those skilled in the art as coming

within the teachings of the present disclosure. Further advantages, objects and uses of the disclosed apparatus will also be apparent. The invention is not to be limited to the exact structures as shown as illustrations of the invention, but only by the appended claims.

I claim:

1. The method of making a sound track on a moving sensitive film, which comprises transmitting a beam of light to the film, and separately varying in accordance with waves of different character, the position of the two edges of the light beam corresponding respectively with the two edges of the sound track. 10

2. The method of recording sound on a moving sensitive film which comprises producing a line of light on the film transversely to the direction of movement of the film, varying the length of the line at one end in accordance with a characteristic of sound, and varying the length of the line at the other end in accordance with another characteristic. 15

3. In apparatus for use in recording sound on a moving photographically sensitive film, means for transmitting a beam of light to the film for tracing a record track thereon, means for varying the position of one edge of the track in accordance with sound wave energy of certain character, and means for varying the position of the other edge of the track selectively in accordance 20 with wave energy of different character. 25

4. In a light controller for use in conjunction with a line source of light in recording sound on a moving sensitive film, a vibratable light modulator and means to vibrate the same to vary the length of the line at one end of the line in accordance with sound controlled current, and another vibratable light modulator and means to vibrate the same to vary the length of said line at the other end selectively in accordance with a current having a characteristic differing from that of said first mentioned current. 30 40

5. In a light controller for use in recording sound on a moving sensitive film, means arranged to define the length of a line of light to be produced on the film, said means including means to vary the length of the line at one end in accordance with sound controlled current and means to vary the length of the line at the other end selectively in accordance with a current having a characteristic differing from that of said first mentioned current. 45 50

6. In apparatus for use in recording sound on a moving sensitive film, means for producing a line of light on the film transversely to the direction of movement of the film, means to vary the length of the line at one end in accordance with sound controlled current, and means to vary the length of the line at the other end selectively in accordance with a current having a characteristic different from that of said first mentioned current. 55 60

7. In apparatus for use in recording sound on a moving photographically sensitive film, means for transmitting a beam of light to the film for tracing a record track thereon, means for varying the position of one edge of the track in accordance with sound wave energy of certain frequency, and means for varying the position of the other edge of the track selectively in accordance with wave energy of different frequency. 65 70

8. In apparatus for use in recording sound on a moving sensitive film, means for defining the length of a line of light to be produced on the film transversely to the direction of movement of the film 75

5 the film, said means including means to vary the length of the line at one end in accordance with sound controlled current within a certain frequency range and means to vary the length of the line at the other end selectively in accordance with a current of a different frequency range.

9. The method of making a sound track on a moving sensitive film, which comprises transmitting a beam of light to the film, vibrating an edge of the light beam corresponding with one edge of the sound track selectively in accordance with high frequency components of a sound wave, and vibrating another edge of the light beam corresponding with the other edge of the sound track selectively in accordance with low frequency components of a sound wave.

10. In apparatus for use in recording sound on a moving sensitive film, means for defining the length of a line of light to be produced on the film transversely to the direction of movement of the film, said means including means to vary the length of the line at one end selectively in accordance with high frequency current and means 20 to vary the length of the line at the other end in accordance with low frequency current.

11. In apparatus for use in making a variable width sound record on a moving sensitive film, means for defining the length of a line of light 30 to be produced on the film transversely of the direction of movement of the film, said means including a vibratable light modulator for varying the length of the line at one end of the line and another vibratable light modulator for varying 35 the length of the line at the other end of the line, means including a frequency selective circuit responsive to sound controlled current for vibrating one of said modulators, and means including another frequency selective circuit responsive to current of a different frequency for 40 vibrating the other of said modulators.

12. In apparatus for use in making a variable width sound record on a moving sensitive film, means for defining the length of a line of light to be produced on the film transversely of the direction of movement of the film, said means including a pair of selectively oscillatable light modulators having a pair of adjacent portions, said modulators extending in opposite directions 45 from said adjacent portions, hinged supports for said modulators at points thereon remote from said adjacent portions, said modulators being so arranged that when oscillating, one modulator varies the length of the line of light at one end 50 of the line and the other modulator varies the length of the line of light at the other end of the line, and means whereby said modulators may be vibrated in accordance respectively with sound controlled currents of different character.

13. A light controller for use in recording sound on a moving sensitive film, including a screen having a slit therein, a pair of separate shutters inclined across the slit and respectively covering opposite ends of the slit, and means responsive to sound controlled current for vibrating said shutters transversely of the slit in accordance respectively with different characteristics of the sound current.

14. In a light controller for use in conjunction 70 with a line source of light in recording sound on a moving sensitive film, a shutter and means to vibrate the same to vary the length of the line at one end of the line in accordance with sound controlled current, and another shutter and 75 means to vibrate the same to vary the length of

said line at the other end selectively in accordance with a current having a characteristic differing from that of said first mentioned current, said shutters being inclined relatively to the line source of light and vibrating transversely to the 5 line.

15. A light controller for use in recording sound on a moving sensitive film, including a screen having a slit therein, a pair of separate shutters inclined across the slit and respectively 10 covering opposite ends of the slit, means responsive to sound controlled current for vibrating said shutters transversely of the slit, and means for causing the vibrations of one of said shutters to be at a lower frequency than that of the other of 15 said shutters.

16. In apparatus for use in making a variable width sound record on a moving sensitive film, means for defining the length of a line of light to be produced on the film transversely of the 20 direction of movement of the film, said means including a shutter having an edge inclined relatively to the line of light and defining one end of the line and another shutter having an edge inclined relatively to the line of light and defining the other end of the line, and means whereby said shutters may be vibrated transversely of the line of light and whereby one of 25 said shutters is responsive to sound current of predetermined frequency and the other of said shutters is selectively responsive to current of a different frequency.

17. In a light controller for use in recording sound on a moving sensitive film, a pair of separately oscillatable mirrors arranged to control the length of a line of light to be produced on the film, and means to oscillate said mirrors to vary the length of the line at both ends in accordance 30 with sound controlled current.

18. In a light controller for use in recording sound on a moving sensitive film, a pair of oscillatable mirrors arranged to control the length of a line of light to be produced on the film, means to oscillate one of said mirrors in accordance with sound controlled current to vary the 40 length of the line at one end, and means to oscillate the other of said mirrors in accordance with a current having a characteristic differing from that of said first mentioned current to vary 45 the length of the line at the other end.

19. In apparatus for use in making a variable width sound record on a moving sensitive film, means for defining the length of a line of light to be produced on the film transversely of the direction of movement of the film, said means including two separately oscillatable mirrors having an edge of one adjacent an edge of the other, said mirrors extending in opposite directions from their adjacent edges and having hinged supports, said mirrors being so arranged that when oscillating, one mirror varies the length of the line of light at one end of the line and the other mirror varies the length of the line of light at the other end of the line, means whereby one of said mirrors may be oscillated in accordance with sound controlled current and whereby the other of said mirrors may be oscillated in accordance with a current having a characteristic differing from that of said first mentioned current.

20. In apparatus for use in making a variable width sound record on a moving sensitive film, means for defining one end of a line of light to be produced on the film, said means including a shutter having an edge inclined relatively to the line of light and another shutter having an edge 70

inclined relatively to the line of light in an opposite sense to that of the first mentioned edge, said inclined edges intersecting each other directly over the center line of the line of light and being vibratable in unison transversely of the line of light while maintaining their point of intersection over said center line, and means responsive to sound controlled current for vibrating said shutters in unison for varying the length of the line of light.

21. A shutter mechanism for use in recording sound on a movable sensitive film, comprising a screen having a slit therein and two separately oscillatable sound controlled shutters, each having an edge inclined across the slit and arranged to control the same end of a line of light to be formed by light passing through the slit, said inclined edges being oppositely inclined with respect to the slit and intersecting each other directly over the longitudinal center line of the slit, and means responsive to sound controlled current for oscillating said shutters in unison, while maintaining the point of intersection of their inclined edges over the center line of the slit.

22. A shutter mechanism for use in recording sound on a movable sensitive film, comprising a screen having a slit therein and two separately oscillatable sound controlled shutters, each having an edge inclined across the slit and arranged to control the same end of a line of light to be formed by light passing through the slit, said inclined edges being oppositely inclined with respect to the slit and intersecting each other directly over the longitudinal center line of the slit, and a single magnet responsive to sound con-

trolled current for oscillating said shutters in unison, while maintaining the point of intersection of their inclined edges over the center line of the slit.

23. In apparatus for use in making a variable width sound record on a moving sensitive film, means for defining the length of a line of light to be produced on the film transversely of the direction of movement of the film, said means including a pair of shutters inclined relatively to the line of light and respectively defining opposite ends of the line, means for vibrating one of said shutters transversely of the line of light in accordance with sound controlled current, and means for vibrating the other of said shutters transversely of the line of light in accordance with the intensity of the sound controlled current.

24. In a light controller for use in recording sound on a moving sensitive film, means for defining the length of a line of light to be produced on the film transversely of the direction of movement of the film, said means including a pair of shutters inclined relatively to the line of light and respectively defining opposite ends of the line, means for vibrating the first of said shutters transversely to the line of light in accordance with sound controlled current, means for detecting said current, means for vibrating the second of said shutters transversely to the line of light in accordance with a component of the detected current, and means for retarding the deenergization of said second shutter as compared with the time required for energization thereof by the detected current.

JACKSON O. KLEBER. 35

CERTIFICATE OF CORRECTION.

Patent No. 2,089,484.

August 10, 1937

JACKSON O. KLEBER.

It is hereby certified that error appears in the printed specification of the above numbered patent requiring correction as follows: Page 2, first column, line 35, strike out the words "transversely of the slit"; line 39, after "13" insert the words vibrate transversely of the slit 7 to; and second column, line 7, after "oscillate" insert transversely of the slit; page 4, second column, line 61, claim 6, for "different" read differing; and that the said Letters Patent should be read with these corrections therein that the same may conform to the record of the case in the Patent Office.

Signed and sealed this 21st day of September, A. D. 1937.

Henry Van Arsdale

(Seal)

Acting Commissioner of Patents.

DISCLAIMER

2,089,484.—Jackson O. Kleber, Long Island City, N. Y. SOUND RECORDING APPARATUS. Patent dated August 10, 1937. Disclaimer filed April 11, 1940, by the assignees, Radio Corporation of America and Electrical Research Products Inc.

Hereby enter this disclaimer to claims 1 to 11, inclusive.
